GRAPHIC FORMING DEVICE

Charles P. Huss, Oak Park Heights, and Frank C. Lunquist, New Brighton, Minn., assignors to Minnesota Mining and Manufacturing Company, St. Paul, Minn.

Filed Oct. 15, 1973, Ser. No. 406,549

Term of patent 14 years

Int. Cl. D18—02

U.S. Cl. D64—11 R

FIG. 4

FIG. 1

FIG. 2

FIG. 5**FIG. 6**FIG. 1 is a front perspective view of a graphic forming device showing our new design;

FIG. 2 is a top plan view thereof;

FIG. 3 is a front elevational view thereof;

FIG. 4 is a rear elevational view thereof;

FIG. 5 is a right side elevational view thereof; and

FIG. 6 is a left side elevational view thereof.

The bottom thereof is essentially free of ornamentation.

It is understood that the circular disk bears graphics adjacent and within its outer edge, and adjacent and within the second ring from its outer edge.

We claim:

The ornamental design for a graphic forming device, as shown and described.
